CARPENTER'S SQUARE.
APPLICATION FILED FEB. 5, 1906.

2 SHEETS—SHEET 2.

UNITED STATES PATENT OFFICE.

GEORGE YATES, OF WYOMING, PENNSYLVANIA.

CARPENTER'S SQUARE.

No. 846,274.

Specification of Letters Patent.

Patented March 5, 1907.

Application filed February 5, 1906. Serial No. 299,520.

To all whom it may concern:

Be it known that I, GEORGE YATES, a citizen of the United States, residing at Wyoming, in the county of Luzerne and State of Pennsylvania, have invented certain new and useful Improvements in Carpenters' Squares, of which the following is a specification, reference being had therein to the accompanying drawing.

10 My invention relates to an improvement in carpenters' squares, and has for its object the provision of a device whereby the carpenter, though possessed of but a rudimentary knowledge of mathematics, may estimate correctly and rapidly the length of rafter having a certain pitch necessary for a structure of given dimensions, thus enabling him to calculate the requisite amount of material without wastage, and by means 15 of which square he can make the upper and lower terminal cuts of the rafter at the proper angles without supplementary tools or calculations.

Further provision is made by which the 20 successive rafters of gables, as well as the valley-rafters, may be quickly estimated and accurately cut without the use of additional tools. Also ready means are afforded for laying off and cutting the frame-timbers 25 for polygonal structures in various situations.

With these objects in view my invention consists in the novel features of construction hereinafter more fully described, illustrated, and claimed.

In the drawing accompanying this specification and forming a part hereof, Figure 1 represents one side of a square constructed in accordance with my invention. Fig. 2 30 shows the reverse side of the square, and Figs. 3 and 4 are diagrammatic views illustrating the manner of use.

Like reference-numerals designate similar parts in all the views.

Referring to the drawing more in detail, 45 2 designates a square having the general form of the ordinary carpenters' square and with divisions indicating decimal parts of a foot, while 1 represents the reverse side of the same square, the divisions marking 50 inches and certain fractional portions thereof—*i. e.*, one-half, one-fourth, one-twelfth, &c. The principle of construction and manner of use of the two sides is the same, the 55 readings differing only according to the frac-

tional unit used in different kinds of work and by preference of the operator.

On the shorter arm of the square, which may be called the "base," a point is located one foot from the corner of the square, and 60 adjacent thereto is described a quadrant 3 about such point as a center.

On the longer arm of the square, which may be called the "altitude," diagonal scores 4 and 5 are formed cutting the graduations 65 (in Fig. 1 the inches and in Fig. 2 the tenths of a foot) and extending in a direct line toward the point 6 on the base, one foot from the corner and forming the center aforesaid of the quadrant 3. These scores, 70 it will be seen, indicate the respective hypotenuses of right-angle triangles having a base one foot long and altitudes corresponding to the graduations intersected by such score.

Each inch and half-inch graduation bears 75 a legend giving the length of the hypotenuse indicated by the score with which it intersects—*e. g.*, the one-inch graduation is marked 1'-0.04"; two inches, 1'-0.16"; three inches, 80 1'-0.36"; eight inches, 1'-2.42", &c., signifying the length of the hypotenuse of a right-angle triangle having a one-foot base and an altitude of one, two, three, and eight inches, respectively.

As a rafter represents the hypotenuse of such a triangle having a base equal to one-half the width of the building and an altitude equal to the vertical distance between the eaves-plate and the ridge-piece, it follows 90 that if a rafter in a building thirty feet wide is to be given a rise of, say, eight inches to the foot it will correspond in pitch to the hypotenuse of a triangle having a base of one foot and an altitude of eight inches. The length 95 of such hypotenuse is shown by reference to the unit-square to be 1'-2.42", and in order to ascertain the exact length of the rafter desired in the building it only remains to multiply the length of this hypotenuse, 1'-2.42", 100 by fifteen, the base in the building, and the required rafter will be found to be precisely 15 by 1'-2.42" or 18'-0.3".

Knowing the number of rafters needed, it 105 is easy to estimate the total amount of material which will be necessary.

To properly cut each rafter, the operator will make two marks on the timber 18'-0.3" apart. He will then place the point 6 at the twelve-inch mark on the base of the square at 110

one of the marks indicated on the timber (as indicated at the left hand of Fig. 3) with the upper edge of the timber coinciding with the score cutting the eight-inch graduation and marked 1'-2.42" and will make the lower terminal horizontal cut of the rafter along the lower edge of the base of the square. He will then place the square with the eight-inch graduation at the mark on the timber (as indicated at the right hand of Fig. 3) with the upper edge of the timber coinciding with said score and intersecting the point 6 on the base of the square and will make the upper terminal cut of the rafter vertically along the outer edge of the altitude of the square. The result will be a rafter of the exact length required for a raise of eight inches to the foot in a building thirty feet wide, and the terminal cuts will be at right angles to each other and respectively horizontal and vertical.

It will be seen that absolutely no calculation is required other than to multiply the value of the score corresponding to the desired pitch by one-half the width of the building, thus providing for rapidity and accuracy in designing, estimating, and framing, and a resultant economy in time and material and greater degree of perfection in workmanship.

In the narrow column 7, Fig. 1, just inside the score-index will be found numerals opposite each inch graduation which govern the amount to be deducted in the cutting of jack-rafters as follows: If the pitch is three inches to the foot and the length of the first rafter of a gable is found to be 12'-4.32" on a twelve-foot base, then the second rafter of the valley in an eighteen-inch run will be 12'-4.32" minus 4.5" (the numeral opposite the three-inch graduation) or 11'-11.82". The third will be 4.5" shorter than the second, and so on to the junction of the ridge and valley. If the rafters are sixteen inches apart, the amount to be deducted from the length of the preceding rafter is four inches instead of 4.5", and the second rafter of the valley would be in the instance given above 12'-4.32" minus four inches, or 12'-.32", and so on.

It will thus be seen that by the use of this square builders are enabled not only to estimate and cut rafters of a straight run, but the varying rafters of a valley without other supplemental tools.

In many classes of work, as in breakers, housework, tinnings' work, &c., it becomes necessary to frame in polygonal structure, and the task of calculating the length of the timbers and the cuts is one beyond the ability of the ordinary carpenter, necessitating the laying off of plans and the reduction of the measurements taken thereon to the work in hand. In the square forming the subject of this application provision is made whereby

such timbers may be laid off and cut with certainty and despatch by the ordinary carpenter.

The lines forming the boundary of a polygonal figure, as is well known, meet at an angle having a value measured by the number of sides in said figure. The sides of a square meet at an angle of ninety degrees, a pentagon at seventy-two degrees, a hexagon at sixty degrees, and so on, while the angles 75 embraced by the sides of such figures are measured by the difference between the meeting angle of the sides and one hundred and eighty degrees. As the sides of an octagon, for instance, meet at an angle of forty-five degrees they embrace an angle of one hundred and eighty degrees minus forty-five degrees, or one hundred and thirty-five degrees, and as in cutting the meeting ends of the timbers the divergent angle is divided 80 equally between the two timber ends each will be cut at an angle of 62.5 degrees to its sides.

To simplify the operation and obviate the necessity of any calculation, and taking advantage of the fact that the two arms of the square meet at an angle of ninety degrees, the quadrant 3 is provided with radial lines 80 alining with the scores 4 on the altitude of the square, which make with that edge of 95 the square angles corresponding to one-half the angles made by the boundary-lines of ordinary polygonal figures.

It will also be noted that along the tongue or base of the square are indicated several 100 polygonal figures for the guidance of the user, illustrating the number of sides in each ordinary polygon and each with a legend, "9," giving the extreme length of a timber forming one side of that polygon constructed 105 within a circle having a radius of one foot. A further legend, "10," gives the cut for the end of each timber to insure a perfect fit.

To illustrate, if a room or roof is to be framed in as an octagon having an extreme 110 radius of ten feet a reference to the octagon figure will show that the length of each side will be 10 by 9.18" or 7'-7.8", and to cut the timbers to fit the square will be placed with the point 6 of the quadrant 3 (which coincides with the twelve-inch graduation of the base of the square) at one edge of the timber and in such position that that edge of the timber coincides with the radial line of the quadrant marked "octagon." The timber is then cut 115 along the outer edge of the longer side of the square. (See Fig. 4.) In placing the square in this position it will be noted that the edge of the timber coincides with the five-inch graduation on the longer arm of the square, as 120 the diagonal score intersecting that graduation alines with the said radial line. By this fact the greatest accuracy is secured in placing the square in position, and for this reason the legend, "10," referring to the cut gives the 125

graduations on each arm of the square which the edge of the timber will intersect, in this instance five inches by twelve inches.

The same application of the square will enable the carpenter to quickly calculate and cut the timbers for framing any polygonal structure with as great accuracy as for square cuts.

Having thus described my said invention, what I claim as new, and desire to secure by Letters Patent of the United States, is—

The herein-described carpenter's square having the short arm or base and the long arm or altitude perpendicular one to the other with their outside edges graduated in inches and half inches from their point of intersection to their ends, said base having the quadrant 3 described about its twelve-inch mark as center, and both the base and altitude having the scores 4 radiating from the twelve-inch mark on the base and intersecting the

inch and half-inch graduations on the altitude, legends adjacent to the graduations on the altitude signifying the length of rafters having a twelve-inch base and a pitch corresponding to the respective graduations, a row of legends on the altitude adjacent to said graduations, the legends of said row signifying the decrease in length of succeeding jack-rafters at the same pitch arranged sixteen and 25 eighteen inches apart, representations of fragments of various polygons on said base and legends upon said base adjacent to said polygons signifying the length of each side based upon a given unit of measurement, substantially as shown and described. 30 35

In testimony whereof I hereunto affix my signature in presence of two witnesses.

GEORGE YATES.
